PROCESS OF TREATING CRUDE SULFATE
SOAP SKIMMINGS

Clarence B. F. Young and Edward J. Calleton,
Leonia, N. J., assignors to National Southern
Products Corporation, New York, N. Y., a cor-
poration of Delaware

No Drawing. Application January 9, 1947,
Serial No. 721,144

5 Claims. (Cl. 260—97.7)

1

The present invention relates to the art of treating crude sulphate soap skimmings to refine them, and more particularly, to a process of converting crude sulphate soap skimmings into a dried soap powder which does not have any of the bad characteristic odors of the material.

It is well known in the paper and pulp industry that when black liquor from the sulphate process is evaporated, a scum, known as black sulphate soap skimmings, separates and floats upon the surface of the black liquor. Generally speaking, such skimmings contain black liquor with sodium sulphide, sodium sulphate, mercaptans, sodium lignate, and many other sulphate paper-mill products.

A typical analysis of the soap skimmings is as follows:

	Per cent
Sodium salts of fatty acids	30
Sodium salts of rosin acids	30
Unsaponifiables	4
Sodium lignate	3
Black liquor solution (10% solids)	33

As the art knows, the black sulphate soap skimmings are an ill-smelling, bad-looking product which has very little use per se in industry. Ordinarily, the soap skimmings are split with sulphuric acid to form crude tall oil. Such splitting gets rid of many of the obnoxious properties. As the acid treatment causes the formation of hydrogen sulphide with sulphur compounds, which in turn are liberated from the tall oil, it can then be used industrially for many operations. Thus, for example, it can be saponified for various uses, or the crude tall oil can be refined by distillation and solvent treatment to get rid of the obnoxious odors and to improve color, etc., after which it can be saponified and used for various soaps, lubricants, etc.

It has been found that when crude sulphate soap skimmings are taken and dried, as in a spray drier, nearly all of the bad properties are eliminated. When crude sulphate soap skimmings are first washed with, for instance, a five per cent sodium chloride solution, or other alkali which will have a tendency to salt out or prevent the soap from going into solution, the soluble products, such as the sodium sulphate and sodium sulphide, will dissolve from the crude sodium sulphate soap skimmings and the resulting material (that is, the washed black sulphate soap skimmings) can be dried in any usual manner. A product is obtained that is superior to black sulphate soap skimmings in that only traces of sodium sulphate, sodium sulphide, and black liq-

uor are present. The odor is good and the resulting material can be used for a variety of things. We prefer to use the skimmings without washing but they may be washed with a salt solution if desired.

In drying it has been found that spray drying is the method best adapted to this type of material because a product can be obtained which is low in moisture and any mercaptans or ill-smelling gases are released from the soap as it dries in small particles in an atmosphere of hot air.

The soap skimmings are atomized and mixed intermittently with large volumes of hot air at a high temperature which removes all but traces 15 of the ill-smelling components of the soap. It is also believed that when water is removed from skimmings down to zero up to about ten per cent the ill-smelling compounds are decomposed and released as gases. Thus, the odor is improved 20 by washing with large volumes of air and by chemical decomposition with heat in the absence of water, the air being heated to a temperature between substantially 400° F. and 700° F. to rapidly vaporize the major portion of the water associated with the soap skimmings and to produce 25 a soap powder having less than 10% of moisture and serving to oxidize ill-smelling sulphur compounds to be taken up by said air and permitting the resulting purified soap powder to be separated 30 from the heated atmosphere of air.

We prefer to first atomize or spray the soap and dry by the method commonly known as "spray drying" because of the large volumes of hot air used. This removes the moisture, decomposes the ill-smelling compounds and then washes them out. This is accomplished in one 35 operation. An illustrative example is given as follows:

A spray tower about 18 feet in diameter and 40 about 18 feet high, equipped with gas air heater, and capable of producing heated air up to 700° F., was used. The suction fan bottom of the tower was approximately four feet in diameter and had six blades. The bottom of the spray tower was equipped with air-propelled sweeper slotted to receive dry material by suction. From the bottom, the material passed to a conical dust collector. The top of the tower was equipped with a high-speed atomizer or sprayer. The material 45 was added to an atomizer or sprayer equipment by gravity feed or by a pump equipped preferably with a Reeves drive.

Approximately 200 pounds of sulphate soap skimmings were dumped into a copper jacketed kettle with a lightning mixer. To the skimmings

was added about 50 pounds of water. This gave a mixture of approximately 50 per cent solids. While the mass was mixing, steam was applied to the jacket and the material was heated to about 160° F. This produced a material which would flow and which was easily pumped to the atomizer or sprayer.

The temperature of the air in the chamber was about 410° F. and the speed of the atomizer or sprayer was about 6200 R. P. M. The rate of flow was about ten pounds of liquid per minute or about five pounds per minute of solid material. A sample was taken off the floor of the spray tower itself. This material had a bead-like form and was very light in weight. The material had good color and excellent odor. Samples were taken from the bottom of the tower itself and also from the conical dust collector. The material passing through the conical dust collector was changed to a powder.

A vacuum drier can be used, if desired, but is not as efficient as a spray drier. In a test run with a four tray vacuum drier, approximately four feet by four feet, using about 25 to 30 mm. of vacuum, the soap was dried in approximately from four to six hours. When originally poured into the pans the material represented approximately 50 per cent solids and covered the bottom of the pan to approximately one-half inch. After being dried, the material was reduced to approximately one-quarter inch and was in a sheet form which broke up very readily into large flakes.

The material had good odor, but it was not quite as good as the spray dried material. In the vacuum drying operation, the vacuum pulled most of the obnoxious odors from the soap skimmings along with the moisture.

A drum drier may be used, but it is the least efficient of the three. This method does not wash the product with gases as in the foregoing operations. It only accomplishes the desired results by heat and by removing water. This type may be used with about 40 per cent solids and about 60 per cent water and introduced on a drum three feet by five feet, equipped with a doctor blade. Steam at 100 pounds' pressure is used in the drum to dry the material poured on the face of the drum. The solution is introduced or fed onto the drum so that the production rate is approximately 300 pounds per hour.

The resulting material, which can be called "tallate" or "sodium tallate," can be used industrially in a number of ways, due to the fact that it does not have a bad characteristic odor. For instance, the material can be used as common soap for household and industrial cleaning. It can also be used as a component of cleaners, such as 15-20 per cent tallate, 50 per cent sodium carbonate, 20 per cent trisodium phosphate, and 15-10 of bentonite. The material can be used as a flotation agent, added directly to the liquid and materials to be separated, as a metal cleaning agent, and as an emulsifying agent.

Various treatments have been proposed to eliminate the objectionable features of black liquor sulphate soap skimmings, but as far as is known, none has been wholly satisfactory and successful, especially when carried into practice on an industrial scale for the production of commercial products.

From the foregoing, it can be seen that great savings can be effected by treating the sulphate soap skimmings directly by the present invention. The practice in the trade at the present time is

to take the crude sulphate soap skimmings, split them with sulphuric acid, produce tall oil and throw away the lignin and the sodium content as sodium sulphate. Ordinary sulphur compounds are liberated as hydrogen sulphide, although a small percentage of these remain dissolved in the crude tall oil which still gives it an objectionable odor. In order to get rid of this odor, the crude tall oil is refined by distillation, solvent process, etc. The refined product is then re-saponified with caustic soda to produce sodium tallate, or the sodium salt of tall oil. It is to be noted that this is the same material that came from the paper mills, but, of course, minus the impurities from sulphate paper manufacture.

In our process the crude sulphate soap skimmings are taken as is, or washed, if necessary, and then are directly heated and dried to produce dry sodium tallate. The sulphur compounds are decomposed and liberated and washed by the large volume of gases so that the resulting material can be used in industry as is. Thus, in one step a product is produced by the present invention which ordinarily requires three steps in prior processes.

It will be understood that the method of the present invention has been described in its preferred form and that various changes or modifications may be made therein without departing from the spirit or scope of the invention as defined in the claims annexed hereto.

Having thus described the invention, what is claimed as new is:

1. A method for the direct production of a purified soap powder from liquid crude sulphate soap skimmings obtained from black liquor which comprises spray-drying said liquid soap skimmings by atomizing the same into an atmosphere of air heated to a temperature from about 400° F. to about 700° F. to form a soap powder having not more than about 10% of moisture and to transform ill-smelling ingredients in said soap skimmings to volatile compounds of relatively inoffensive odor taken up by the said atmosphere and separating the resulting soap powder from the said atmosphere while in a heated condition to retain the moisture therein.

2. A method for the direct production of purified soap powder from liquid crude sulphate soap skimmings obtained from black liquor which comprises heating said liquid soap skimmings to a readily-flowing consistency, feeding the heated soap skimmings by gravity feed to a high speed atomizer, washing the atomized soap skimmings with a large volume of air without the addition of water, said air being heated to a temperature between substantially 490° F. and 700° F. to rapidly vaporize the major portion of the water associated with the soap skimmings to produce a soap powder having less than 10% of moisture and serving to oxidize ill-smelling sulphur compounds to be taken up by said air and separating the resulting soap powder from the heated atmosphere of air.

3. A method for the direct production of purified soap powder from liquid crude sulphate soap skimmings obtained from black liquor which comprises heating said liquid soap skimmings to a temperature of about 160° F. to produce a readily-flowing consistency, feeding the heated soap skimmings to an atomizer in a spray drying apparatus containing air heated to a temperature between about 400° F. and 700° F. to vaporize water from the soap skimmings so as to produce a soap powder therefrom having not more than

10% of moisture and from which ill-smelling ingredients have been removed by transformation into volatile relatively inoffensive compounds taken up by the heated atmosphere, collecting the soap powder and separating the soap powder from the heated atmosphere of air.

4. A method for the direct production of purified soap powder from liquid crude sulphate soap skimmings obtained from black liquor which comprises washing the crude sulphate soap skimmings with a salt solution to prevent the soap therein from going into solution yet dissolving soluble salts therefrom, spraying the thus partially purified liquid soap skimmings into an atmosphere of air at a temperature of about 410° F. to remove moisture from the soap material and to oxidize ill-smelling ingredients originally contained in the liquid soap skimmings, said oxidized ingredients being taken up by the atmosphere of air while soap powder having not more than 10% of moisture content is precipitated in the said atmosphere and removing the said precipitated soap powder from the heated air while at a temperature to retain the moisture below the figure given above.

5. A method for the direct production of purified soap powder from liquid crude sulphate soap skimmings obtained from black liquor which comprises washing the crude sulphate soap skimmings

with a solution of sodium chloride to dissolve sodium sulphide and other soluble salts therefrom without dissolving any substantial amount of soap therein, heating the partially purified liquid soap skimmings to a readily flowing consistency, feeding the heated liquid soap skimmings to an atomizer in a chamber containing a relatively large volume of air heated to a temperature between about 400° F. and 700° F., to absorb the moisture from the liquid soap skimmings and to decompose the ill-smelling constituents from the said liquid soap skimmings to be released as gases into the said air, and collecting the purified soap powder.
